INVENTOR.
Harry E. Stalter,
BY Walter N. Haskell,
his ATTORNEY

UNITED STATES PATENT OFFICE.

HARRY E. STALTER, OF MOLINE, ILLINOIS.

CUT-OFF SLIDE ATTACHMENT.

Application filed May 2, 1921. Serial No. 466,185.

To all whom it may concern:

Be it known that I, HARRY E. STALTER, a citizen of the United States, residing at Moline, in the county of Rock Island and State 5 of Illinois, have invented certain new and useful Improvements in a Cut-Off Slide Attachment, of which the following is a specification.

My invention has reference to a cut-off 10 slide attachment, such as are used with turret lathes, and has for its purpose to facilitate the operation of producing washers from a piece of tubing. In some cases the washers which are cut from the tubing 15 possess so little thickness that it is a difficult matter to pick them up. As they are severed from the end of the tube they fall into the oil and filth with which the machine is surrounded, and after the machine is 20 stopped considerable time is consumed in recovering the washers and sorting them, and many of them are not recovered at all.

By the use of the present invention the washers are collected as they are formed, 25 and can be quickly removed for the purpose of packing or storing the same. It is also possible by the use thereof to keep the different sizes of washers in separate groups.

In the drawings:

30 Fig. 1 shows the fragmentary part of a turret lathe, with my invention attached thereto, in side elevation.

Fig. 2 is a transverse section, on the line 2-2 of Fig. 1.

35 Fig. 3 is an enlarged view of the invention, detached.

1 represents a portion of the table of a 40 turret lathe, and 2 a head mounted thereon, and provided with a cutter-block 3, carrying a knife 4. 5 indicates the end of a lathe, in which is held a tubular member 6, so as to be fed gradually toward the knife 4. In practice several of the knives 4 would be 45 employed, each one making a partial cut on the tube. The knife 4 is assumed to be the one which will perform the final operation, by means of which a ring, or washer will be completely severed from the tube.

50 Fixed to the head 2 is a plate 7, by means of a bolt 8 secured in said head, and passing through an opening in one end of the plate. The opposite end of said plate is perforated to receive a rod 9, which can be held in ad-

justed positions therein, vertically, by means of a thumb-screw 10. The lower end 55 of the rod 9 is provided with an opening to receive the threaded end of a rod 11, of less diameter than the rod 9, and held in place by nuts 12 and 13 on opposite sides of the rod 9. The rod 11 passes through an opening 14 in the head 3, and has its free end in proximity to the knife 4. Said rod is also 60 preferably inclined upwardly toward said knife.

The end of the rod 11 is sufficiently close 65 to the knife 4 to catch the washer as it is severed by such knife, the washer moving downwardly along the rod by force of gravity, or by pressure from the next succeeding washer as it is severed from the tube. 70 A series of the washers is thereby strung upon the rod 11, and can be easily slipped therefrom by the hand of the operator when it is desired to remove same.

It is evident that the rod 11 can be 75 brought into proper position, vertically, by adjustment of the rod 9, and longitudinally by means of the nuts 12 and 13. If at any time it is desired to use the machine without the attachment the rod 9 can be disconnected 80 from the plate 7, leaving such plate in position on the machine.

If desired, the opening in the plate 7 through which the bolt 8 passes, indicated in broken lines at 15, can be of elongated form, 85 so as to permit a quick adjustment of the rod 11, longitudinally.

What I claim and desire to secure by Letters Patent, is:

1. A device of the class described, comprising a plate adapted for attachment to the head of a turret lathe; a rod supported vertically in said plate; and a rod of smaller diameter than said first-named rod, supported thereby so as to have its free end in 95 proximity to the cutting device of said head.

2. A device of the class described, comprising a horizontal supporting member, adapted for attachment to the cut-off slide of a turret lathe; a vertical member connected with said supporting member; and a rod supported by said vertical member in approximate parallel relation with said horizontal member, and so as to be capable of adjustment with relation thereto. 100

3. A device of the class described, com-

prising a plate adapted to be secured in horizontal position on the cut-off slide mechanism of a turret lathe; a vertical rod secured in said plate, so as to be capable of 5 rotation therein; means for adjustment of said rod, vertically; a rod of smaller diameter than said first-named rod, supported

in the lower end thereof, and inclined upwardly into juxtaposition with the cutting devices of said slide; and means for adjustment of said last-named rod, longitudinally. 10

In testimony whereof I affix my signature.

HARRY E. STALTER.
